ROAST TRAY

James B. Swett, 8 Devonshire Drive, Barrington, R.I.

Filed Nov. 16, 1961, Ser. No. 67,552

Term of patent 14 years

(Cl. D44—10)

FIG. 1.

FIG. 2.

FIG. 3.

FIG. 4.

FIG. 5.

FIG. 1 is a top plan view of a roast tray showing my new design;

FIG. 2 is a bottom plan view of the same;

FIG. 3 is a side view of the same;

FIG. 4 is an end elevational view of the same; and

FIG. 5 is a cross-sectional view on the line 5—5 of FIG. 3.

I claim:

The ornamental design for a roast tray, as shown.
